UNITED STATES PATENT OFFICE.

JESSE D. RICHARDS, OF LA FONTAINE, INDIANA, ASSIGNOR OF ONE-FOURTH TO ANSON C. RICHARDS, OF TREATY, INDIANA, AND ONE-FOURTH TO JOSEPH L. DAVIS AND ONE-FOURTH TO CARRIE L. DAVIS, BOTH OF LA FONTAINE, INDIANA.

SOCKET WRENCH.

Application filed March 11, 1926. Serial No. 94,018.

This invention relates to socket wrenches and more particularly to socket wrenches for use in removing the nuts and bolts employed in holding the fish plates to track rails.

5 A further object of the invention is to provide a device of this character which will remain firmly in engagement with the nut or bolt head during the entire operation of removing the nut.

10 In such devices heretofore constructed, the arrangement of the parts has been such that the point at which the socket engages the nut and the point of effective engagement 15 of the handle therewith are so arranged that oscillation of the handle tends to tip the socket upon the nut with the result that the handle wobbles and the socket becomes disengaged from the nut unless constant attention is given the same. Furthermore, in 20 ratchet wrenches of this type, the ratchet pawl as carried by the handle is engaged with the socket either in alignment with the handle or inwardly of the handle with respect to the open face of the socket and thus 25 the thrust applied from the handle to the socket tends to wedge the handle outwardly away from the nut and rail with the result that the socket constantly tends to 30 move outwardly upon the nut and eventually releases therefrom. An important object of this invention is to produce a device in which the arrangement is such that these difficulties are overcome.

35 These and other objects I attain by the construction shown in the accompanying drawing, wherein for the purpose of illustration is shown a preferred embodiment of my invention and wherein:—

40 Figure 1 is a side elevation of a socket wrench constructed in accordance with my invention;

Figure 2 is a front elevation thereof;

45 Figure 3 is a section on the line 3—3 of Figure 2.

In accordance with my invention, I provide a handle member 10 which, adjacent one end, is offset, as at 11. The offset portion 11 provides a journal, as at 12, for the shank 13 of a socket 14, which socket is arranged at that side of the offset portion 11 underlying the bight 15 produced in offsetting the handle. Any suitable means may

be provided for removably retaining the stem 13 within the journal 12 as, for example, a 55 cotter pin 16. Immediately above the bight 15 of the offset, the handle 10 has mounted therein a pivot 17 upon which is mounted a pawl element 18 for coaction with ratchet teeth 19 formed upon the exterior of the 60 socket. The pawl 18 swings from side to side of the bight 15 to determine the direction of ratchet movement. It will be noted that the handle 10 operates in a plane lying more nearly adjacent the open mouth 65 19 of the socket than the point of engagement of the pawl therewith so that strain applied by the pawl to the handle will tend to urge the free end of the handle toward the plane of the open end of the socket. When 70 in this position, the handle operates in substantially the plane of the nut N engaged in the socket so that there is little tendency of the handle to wobble or of the socket to move outwardly upon the nut.

75 Since the construction hereinbefore set forth is obviously capable of a certain range of change and modification without materially departing from the spirit of the invention, I do not limit myself to such specific structure except as hereinafter claimed.

I claim:—

1. A ratchet socket wrench comprising a handle having an offset adjacent one end, a journal carried by said end, a socket rotatable in said journal and underlying the bight of the offset, a pivot carried by the handle above the offset and a pawl upon said pivot and overlying the bight of the offset, there being ratchet teeth upon the 90 socket for engagement by the pawl.

2. In a ratchet socket wrench, a handle having a transverse journal in one end thereof, a socket rotatable in said journal and provided immediately adjacent the face of the handle with ratchet teeth, the handle being offset immediately above the socket the bight of the offset overlying the socket and a pawl pivoted to the opposite face of the handle from the socket and at the opposite side of the offset of the handle from the socket for engagement with the ratchet teeth of the socket.

In testimony whereof I hereunto affix my signature.

JESSE D. RICHARDS.
